OF TOLEDO, OHIO

SOUND INSTRUMENT

Application filed May 16, 1929. Serial No. 363,427.

My invention has for its object to provide a toy sound instrument of the "kazoo" type, wherein voice sound vibrations are modified by a diaphragm. The invention particularly has for its object to provide an efficient instrument of the character described which is so constructed as to produce clear modulated tones. Preferably, the body of the instrument is formed of plastic material and the diaphragm is so shaped as to produce clearly modulated voice tones. A means is provided for maintaining the diaphragm in the required shape.

The invention may be contained in instruments that vary in their details and, to illustrate a practical application of the invention, I have selected two forms or embodiments of the invention and shall describe them herein-after. The constructions selected for purposes of illustration are shown in the accompanying drawing.

Fig. 1 illustrates a front view of an embodiment of the invention. Fig. 2 illustrates a view of a section taken on the plane of the line 2—2 indicated in Fig. 1. Fig. 3 illustrates a front view of a second embodiment of the invention. Fig. 4 is a view of a section taken on the plane of the line 4—4 indicated in Fig. 3.

In the form of construction illustrated in Figs. 1 and 2, a hollow body having a tapering chamber formed of a plastic material, such as a confection, is provided with a mouth piece 1, located at one end of the tapering chamber 2, and a diaphragm 3 that closes the other end of the chamber 2. Where the body of the instrument is formed of paraffin gum, a washer 4 is located at the edge of the chamber 2 and within the diaphragm 3. The washer 4 forms a rigid material for securing the edge of the diaphragm 3. The edge of the diaphragm 3 may be secured to the washer 4 or, if the material of which the body of the instrument is formed is sufficiently rigid, when chilled, the washer 4 will be secured to the edge of the diaphragm 3 by the adhesive character of the material, the two being joined thereby when the material is warm or sufficiently plastic to penetrate beneath the surfaces of the washer 4, the central por-

tion of the diaphragm is depressed and when the washer 4 is secured to the edge of the diaphragm, the washer 4 prevents the return of the diaphragm 3 to its normal flat condition. Thus, the washer 4 operates to hold the diaphragm concave on the outer side of the diaphragm.

The diaphragm 3 is, preferably, formed of an elastic material and slightly rigid, such as cardboard, and when the central portion is depressed, it forms a radial wrinkle or ridge 5. This in effect is a reduction of the length of the periphery of the diaphragm 3 and, when it is secured to the washer 4, it operates to hold the diaphragm in its concave form. In the formation of the instrument shown in Figs. 1 and 2, where it is formed of paraffin gum, the washer 4 may be placed on a ledge 6 formed near the larger end of the chamber 2 of the instrument, and a plunger having a suitable form and slightly warmed, may be forced against the diaphragm to produce the gather or ridge 6 and produce the desired concavity of the diaphragm 3. Preferably, the diameter of the plunger is slightly larger than the interior diameter of the end of the instrument which operates to push down a small quantity 7 of the paraffin material against the outer edge portion of the diaphragm. This forms a second ledge for securing the diaphragm in position and also to cause adhesion through the paraffin as between the washer and the diaphragm. Where the diaphragm is depressed in the paraffin, apart from the washer, the paraffin is ordinarily not sufficiently rigid at ordinary temperatures to prevent the expansion of the periphery of the diaphragm and, consequently, to prevent the diaphragm from returning to its normal flat condition by reason of its elasticity. The washer thus operates to retain the diaphragm in its concave form notwithstanding its elasticity.

In order to prevent creation of pressure within the chamber 2 by reason of the operator blowing into the chamber 2, and causing the outward distension of the diaphragm, an opening 10 is formed in the body of the instrument to allow the escape of the air. Thus, the diaphragm is retained in its con-

cave form which enables the production of clear voice modulated tones.

In the form of construction shown in Figs. 3 and 4, a shallow shell 15, circular in form, is suitably secured to a handle 14. Preferably, the shell 15 is formed of candy that is rendered plastic by heat and at ordinary temperatures is hard. Moreover, it is very adhesive in its character and when the diaphragm 16 is depressed within the edge 17 of the shell, and the periphery is heated, the shell will operate to secure the edge of the diaphragm in the concave form produced by the formation of the wrinkle or ridge 18. Preferably, the edge of the shell 15 is provided with a ledge 19 and a plunger member is shaped to form the central radial ridge 18 when it is pressed against the diaphragm 16. The diaphragm 16 is secured in the shell 15 by either heating the edge of the plunger so as to heat the ledge 19 and thus render it plastic, or the ledge 19 may be wetted in advance of the placement of the diaphragm 16 to render it adhesive to the periphery of the diaphragm 16 when the diaphragm 16 is placed in position. The hard candy will hold the diaphragm in its concave formation and produce clear modulated voice tones.

Preferably, the handle 14 is a stick and the shell 15 conforms to a shape of a small "lollipop" which makes the instrument extremely attractive to children.

I claim:

1. In a sound instrument, a shell having a chamber, a mouthpiece communicating with the chamber, a concave diaphragm forming a wall of the chamber to close the chamber and secured throughout the entire length of its periphery to the edge of the shell.

2. In a sound instrument, a shell having a chamber, a mouthpiece communicating with the chamber, a concave diaphragm forming a wall of the chamber to close the chamber and secured throughout the entire length of its periphery to the edge of the shell, the shell having an opening between the mouthpiece and the diaphragm communicating with the chamber for preventing the creating of air pressure within the interior of the shell.

3. In a sound instrument, a shell formed of a plastic material and having a chamber, a mouthpiece communicating with the chamber, a diaphragm for closing one end of the chamber, the shell having a ledge engaging the peripheral portion of the inside of the diaphragm and a ledge engaging the peripheral portion of the outside of the diaphragm.

4. In a sound instrument, a shell having a chamber, a mouthpiece communicating with the chamber, an annular member, a concave diaphragm, the periphery of the diaphragm connected to the annular member, and means for securing the annular member and the

diaphragm to the edge of the shell for closing one end of the chamber.

5. In a sound instrument, a shell having a chamber, a mouthpiece communicating with the chamber, a concave diaphragm for closing one end of the chamber, the shell formed of a plastic material and having a ledge engaging the peripheral portion of the inside of the diaphragm and a ledge engaging the peripheral portion of the outside of the diaphragm for maintaining the concave formation of the diaphragm.

6. In a sound instrument, a shell having a chamber, a mouthpiece communicating with the chamber, the edge of the shell having a ledge, a washer located in contact with the ledge, a concave diaphragm, the periphery of the diaphragm located in contact with the washer, the shell having a second ledge in contact with the exterior of the peripheral portion of the diaphragm, and means for securing the washer to the peripheral portion of the diaphragm.

7. In a sound instrument, a mouthpiece, a shell having a chamber, one end of the chamber communicating with the mouthpiece, a concave diaphragm of relatively stiff material forming a wall of the chamber, the diaphragm secured along its edge to the instrument and completely closing the chamber except for the mouthpiece.

8. In a sound instrument, a mouthpiece, a concave diaphragm, a shell having a chamber, one end of the chamber communicating with the mouthpiece, the other end having two ledges, a washer located in contact with the interior ledge, the periphery of the diaphragm located in contact with the washer, the exterior ledge located in contact with the exterior of the peripheral portion of the diaphragm, and means for securing the washer to the peripheral portion of the diaphragm.

In witness whereof I have hereunto signed my name to this specification.

HUBERT A. MYERS.
